D16536

UNITED STATES PATENT OFFICE.

WILLIAM W. JACKSON, OF PHILADELPHIA, PENNSYLVANIA, ASSIGNOR TO
ARTHUR M. AND ALSON E. BARNHART, OF CHICAGO, ILLINOIS.

DESIGN FOR A FONT OF PRINTING-TYPE.

SPECIFICATION forming part of Design No. 16,536, dated February 16, 1886.

Application filed July 16, 1885. Serial No. 171,812. Term of patent 14 years.

To all whom it may concern:

Be it known that I, WILLIAM W. JACKSON, a citizen of the United States, residing in the city of Philadelphia, county of Philadelphia, 5 and State of Pennsylvania, have invented and produced a new and original Design for a Font of Printing-Types, of which the following is a specification, reference being had to the accompanying typographical illustration, forming a part hereof.

The general character of my design is a combination of certain features of the Old Style letter with certain features of the Celtic letter. It has a shade or outline, is of medium weight, 15 slightly extended, and somewhat ornamented, and consists of capitals, lower-case letters, figures, points, character &, and dollar-mark, also an additional form of capital O, with a heavy shaded bar extending obliquely downward from right to left, and two ornaments.

The peculiar distinguishing features are, first, that of the vertical and inclined initial and terminal lines, the outward boundary curves outward and the inner boundary curves 25 inward at the top or bottom, or both, thus forming on such lines a sharp-pointed caved ceriph, blending gradually with the line; second, that the shades or outlines stand detached from the bodies of the line, to which 30 they respectively pertain, except where in some cases the shade or outline of a curve is necessarily made to seem to disappear behind the body of the line, and seems to join it, as in the vertical strokes of capital M, where the 35 outline seems to join the ceriph at the bottom,

and in the capital O, wherein the outside shade line seems to join the body at the lower left hand.

Capital A of my design has a heavy horizontal line extending across the top of the letter, curving up at each end of the same, thence slanting down and outward, the cross-stroke connecting the two angles being curved. The heavy diagonal lower right-hand stroke, capitals K and R, cross the connecting line and project slightly into the center of the letter. The Old Style Celtic character is preserved in the design of the lower-case letters.

A special feature is shown in formation of lower-case e. The cross-line, instead of extending in a horizontal direction, is drawn obliquely toward the upper curved portion, where it connects, thus completing the letter. Lower case g is formed by a half-circle at the left side, above the line, while the perpendicular stroke extending below the line ends in a curve to the left with a swell.

All the figures are uniform, in that they do not present an irregular appearance, extending above and below the line.

I claim—

The design for a font of printing-types herein shown and described, having body-lines medium heavy, shade-lines detached, and ceriphs, wherever they appear, light and tapering off from the body-lines to sharp points.

WM. W. JACKSON.
